A. H. Struve

INVENTOR

BY *Victor J. Evans*

ATTORNEY

UNITED STATES PATENT OFFICE.

ALBERT H. STRUVE, OF POCATELLO, IDAHO.

WASHING DEVICE.

1,390,176.

Specification of Letters Patent.

Patented Sept. 6, 1921.

Application filed November 8, 1920. Serial No. 422,667.

To all whom it may concern:

Be it known that I, ALBERT H. STRUVE, a citizen of the United States, residing at Pocatello, in the county of Bannock and 5 State of Idaho, have invented new and useful Improvements in Washing Devices, of which the following is a specification.

This invention relates to a bath room attachment, the principal object of the invention being to automatically mix soap and the like with the bath water as the water passes to the spray brush or nozzle.

Another object of the invention is to provide means for regulating both the amount 15 of water and the amount of soap passing from the attachment.

This invention also consists in certain other features of construction and in the combination and arrangement of the several 20 parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a longitudinal sectional view 30 through the device.

Fig. 2 is a section on line 2—2 of Fig. 1.

Fig. 3 is a section on line 3—3 of Fig. 1.

In these views 1 indicates a cylindrical container, which has the end covers 2 screw 35 threaded thereon and the container is divided into two chambers by the partition 3, this partition having the outlet nozzle 4 and the nipple 5. A rubber bulb 6 adapted to contain liquid soap or the like has its mouth 40 connected with one end of the nozzle 4, said bulb being in one chamber and an outlet pipe 7 is located in the other chamber and has its end secured to the outer end of the nozzle 4. This chamber also has located 45 therein the curved water pipe 8, which has one end connected with the nipple 5. A valve 9 is located in the pipe 7 and the stem 10 of this valve passes to the exterior of the container where it is provided with a handle 11. A valve 12 is located in the water pipe 8 and the stem 13 of this valve passes to the exterior of the container and is provided with a handle 14. The cap or cover 2 at the 50 bottom is provided with the nipple 15 for receiving the water tube which conveys the

water from the device to the spray brush or similar device. The pipe 7 has its lower end extending into the nipple so as to deliver the soap to the water as the same is passing from the container, the outlet end of the water 60 pipe being located a distance above the bottom of the container.

Cap 2' has screw threaded engagement with the upper end of the container. This cap is made large enough to form a chamber to receive a cake of soap or the like, the cake being supported by means of a screen 2" which rests on the upper end of the container and is held in place by a shoulder on the cap. 70

Water is supplied to the device through the branch pipe 16 which leads the water into the two chambers of the device as shown. The flow of water through this pipe 16 can be controlled by means of the valve 75 17. By manipulating this valve water can be made to enter either the upper or the lower chamber as desired.

It will be seen that as the water under pressure enters the upper part of the container it will act to compress the rubber bulb so as to force the soap therein through the pipe 7, the amount of soap passing through said pipe being controlled by valve 9. The water will pass through pipe 8, its 85 passage therethrough being controlled by the valve 12 and will pass from the lower end of the container through the nipple 15 and the tube which leads it to the spray brush. This water will be mixed with the 90 soap so that a mixture of soap and water will be delivered from the brush.

The water in the upper chamber coming in contact with the cake of soap in the cap 2' will dissolve the soap so that the water 95 passing through pipe 8 will also contain a quantity of soap. If it is desired to use the device without the soap this can be done by moving valve 17 to cause the water to pass into the lower chamber so that this water 100 will flow direct to the spray device and will be free of soap. It will be understood that a cake of soap can be placed in the cap 2' and used with the liquid soap or either the cake of soap or the liquid soap can be dispensed with, as desired.

It is thought from the foregoing description that the advantages and novel features of my invention will be readily apparent.

I desire it to be understood that I may 110

make changes in the construction and in the combination and arrangement of the several parts, provided that such changes fall within the scope of the appended claims.

5 What I claim is:—

1. A device of the class described comprising a container, a partition in said container dividing the same into two chambers, a compressible receptacle in one chamber supported by the partition, means for introducing liquid into said chamber, an outlet pipe in the other chamber and in communication with said receptacle, an outlet nipple connected with the last mentioned chamber, a 10 water pipe in said other chamber in communication with the upper chamber, valves

in said pipes and means for controlling the valves from the exterior of the casing.

2. A device of the class described comprising a container having a partition therein 20 dividing the same into upper and lower chambers, a compressible receptacle in the upper chamber, an outlet pipe in the lower chamber and in communication with said receptacle, a pipe connecting the upper 25 chamber with the lower part of the lower chamber, a branch supply pipe having its ends connected with the two chambers and a valve in said pipe for directing the water to either chamber.

30 In testimony whereof I affix my signature.
ALBERT H. STRUVE.
